UNITED STATES PATENT OFFICE.

ANNIBALE BERETTA, OF MILAN, ITALY, ASSIGNOR TO MARTINI & HÜNEKE MASCHINENBAU-AKTIEN-GESELLSCHAFT, OF BERLIN, GERMANY, A CORPORATION OF GERMANY.

STORAGE PLANT FOR INFLAMMABLE LIQUIDS.

1,186,269.

Specification of Letters Patent.

Patented June 6, 1916.

Application filed September 30, 1913. Serial No. 792,576.

To all whom it may concern:

Be it known that I, ANNIBALE BERETTA, a citizen of the Kingdom of Italy, and resident of Milan, Italy, have invented certain 5 new and useful Improvements in Storage Plants for Inflammable Liquids, of which the following is a specification.

This invention relates to storage plants for inflammable liquids in which the inflammable liquid is drawn off by means of a 10 heavy incombustible liquid, and a primary object is to provide that no inflammable liquid shall issue in the event of the discharge pipe fracturing.

One illustrative embodiment of the invention is diagrammatically represented by way of example in the accompanying drawing, the figure shown being a sectional elevation of one form of apparatus according 15 to the invention.

The tank 1, in which the inflammable liquid indicated by vertical dotted lines is stored, is connected to the tank 2 containing the incombustible liquid, *e. g.* water, glycerin or the like indicated by horizontal dotted lines, by a pipe 3 which opens at one end at the bottom of the tank 2 and extends to the bottom of the tank 1 and contains a cock 6. A pipe 3^a branches off from the 20 pipe 3 and contains a cock 5 and a pump 4. The delivery port of said pump is connected with the lower portion of the pipe 3, and the suction port with the cock 5 and with the upper portion of said pipe 3, so 25 that operation of the pump will produce a partial vacuum in the upper portion of the pipe 3. Another cock 6 is located in the pipe 3 between the two points at which it communicates with the pipe 3^a. A pipe 7 has 30 one end connected to the top of the tank 1 and has at its other end a draw-off cock 9. Both the pipe 7 and the cock 9 are surrounded by a second pipe 8 which forms 35 with the former an annular protective chamber which is connected by the pipe 10 with the upper part of the pipe 3.

The inflammable liquid is drawn off by running incombustible liquid into the tank 1. To do this it suffices to open the cock 5

and to work the pump 4 for a short time 50 until the incombustible liquid flows (which can be ascertained by listening); the pressure in the pipe 10 and in the annular chamber in the pipe 8 is thereby reduced. It now suffices to close the cock 5 and to open the 55 cock 6 in order that the incombustible liquid may be siphoned from the tank 2 into the tank 1, so that the inflammable liquid can be drawn off at the cock 9. Now if the delivery pipe 7 and the surrounding pipe 8 are 60 broken while inflammable liquid is being run off the air will at once enter into the pipe 10 and consequently stop the siphon action; no more inflammable liquid can then issue from the delivery pipe as no more in- 65 combustible liquid flows to the tank 1. It is to be noted that the pump 4 has to be operated only when first starting the plant, because when the cock 6 is closed the incombustible liquid remains in the pipe 3 above 70 the cock, so that afterward, when it is desired to draw off the inflammable liquid, it suffices to open the cock 6 and the siphon action will at once start again.

I claim:

The combination of a storage tank for storing inflammable liquids, a second tank for containing an incombustible liquid, said second tank being located at a higher level than the storage tank, a siphon pipe leading 80 from the bottom of the second tank to the bottom of the storage tank, a delivery pipe connected to the top of the storage tank, a protective chamber surrounding the delivery pipe, a pipe connecting said chamber 85 with the top of the siphon pipe, and means for producing a partial vacuum in the siphon pipe and in said chamber and thereby enabling liquid to be siphoned out of the second tank into the storage tank. 90

In testimony whereof, I have hereunto set my hand in the presence of the subscribing witnesses.

ANNIBALE BERETTA.
